UNITED STATES PATENT OFFICE.

DAVID F. HEVERLY, OF CENTRE POINT, IOWA.

DESIGN FOR A GAME-BOARD.

SPECIFICATION forming part of Design No. 26,500, dated January 5, 1897.

Application filed November 28, 1896. Serial No. 613,837. Term of patent 14 years.

To all whom it may concern:

Be it known that I, DAVID F. HEVERLY, a citizen of the United States, residing at Centre Point, in the county of Linn and State of Iowa, have invented and produced a certain new and original Design for a Game-Board; and I do declare the following to be a full, clear, and exact description of the invention, such as will enable others skilled in the art to which it appertains to make and use the same.

My invention has relation to a new and original design for a game-board.

It relates to the entire configuration of the game-board, as shown in the accompanying drawings.

My invention relates particularly to a game-board as illustrated in the accompanying drawings, in which—

Figure 1 is a perspective view of a game-board embodying my design, and Fig. 2 is a transverse section of the same.

The leading features of my design appear in the following description.

1 represents a plane board having a circular pocket 2, located exactly in the center.

This pocket is surrounded by an inclined flange 3, extending entirely around the outside edge of said pocket, as shown in the drawings.

4 4 4 4 represent a series of four hemispherical recesses located equidistant from the center of the pocket 2 and equidistant from each other.

The contour of the board is that of a four-pointed star, as shown in Fig. 1, and the entire outer edge of the board is surrounded by a raised rail 5, with the exception of the apex of each of the points of the star, where an opening 6 is left.

Having thus fully described my design, what I claim as new and original, and desire to secure by Letters Patent of the United States, is—

The design for a game-board, substantially as herein shown and described.

In testimony whereof I hereunto affix my signature in presence of two witnesses.

DAVID F. HEVERLY.
